UNITED STATES PATENT OFFICE

126,981

DESIGN FOR A DISPLAY CASE OR THE LIKE

Parker H. James, Indianapolis, Ind.

Application February 6, 1941, Serial No. 98,792

Term of patent 14 years

To all whom it may concern:

Be it known that I, Parker H. James, a citizen of the United States, residing at Indianapolis, in the county of Marion and State of Indiana, have invented a new, original, and ornamental Design for a Display Case or the like, of which the following is a specification, reference being had to the accompanying drawing, forming a part thereof.

The single view in the drawing is a front per-

spective view of a display case or the like embodying my new design.

The opposite end of the display case is identical with the end shown and the rear side of the display case is plain.

I claim:

The ornamental design for a display case or the like, substantially as shown and described.

PARKER H. JAMES.
